Assistant Examiner — Altaira J Swangin

(57) **CLAIM**

The ornamental design is for a keyboard base for portable computer, as shown and described.

DESCRIPTION

FIG. 1 is a top, front and right side perspective view showing my new design;

FIG. 2 is a top, rear and left side perspective view thereof;

FIG. 3 is a bottom, rear and left side perspective view thereof;

FIG. 4 is a front view thereof;

FIG. 5 is a rear view thereof;

FIG. 6 is a left side view thereof;

FIG. 7 is a right side view thereof;

FIG. 8 is a top view thereof;

FIG. 9 is a bottom view thereof; and,

FIG. 10 is another top front right perspective view of the keyboard base for portable computer of FIGS. 1-9, shown in use with the environment of a portable computer installed on my new design.

1 Claim, 8 Drawing Sheets
